UNITED STATES PATENT OFFICE

BOWDEN WASHINGTON, OF NEW YORK, N. Y., ASSIGNOR TO REMOTROLE CORPORATION,
A CORPORATION OF NEW YORK

RADIORECEIVER

Application filed February 9, 1927. Serial No. 166,992.

One object of my invention is to produce a remote controlled radio receiver in which the wave length to which it best responds and the volume of the output may be controlled 5 from a distant point.

Another object is to produce an attachment for existing receivers to attain the above mentioned results. The modern broadcast receiver has sufficient undistorted output to 10 be clearly heard anywhere on a single floor of the average dwelling house or anywhere in the average apartment. A receiver of this type is too large and heavy to be conveniently movable from room to room. Yet, it is most 15 annoying for the listener to have to remain by the receiver in order to effect a change of program, when desired, or to be continually getting up and going to the receiver to change the program or the volume.

20 One object is to provide a method of reception and control which will make it possible for the operator to enjoy such program as he desires with a minimum effort.

By means of my invention, which will not 25 add prohibitively to the cost of the receiver, both these adjustments may be effected from a distance. The control box may be made small and light enough to be readily portable. Its power may be supplied from the 30 alternating current house mains and it may be provided with a cord and plug so that it may be attached to any existing lamp socket, base plug or other outlet.

35 Referring to the drawings, Fig. 1 is a schematic wiring diagram of a receiver embodying one form of my invention with a schematic wiring diagram of its control station.

Fig. 2 is a diagrammatic drawing of another form of apparatus of my invention.

Fig. 2^a is a diagram showing one arrangement of circuits for the oscillating high frequency detector of Fig. 2.

40 Fig. 3 is a partly schematic and partly diagrammatic drawing of a form of my invention which may be readily associated or used with the usual tuned radio frequency receiver or other sufficiently sensitive sets.

45 In Fig. 1 the antenna 5 is connected to the ground 6 through the primary 7 of the band

amplifying transformer 7' consisting of the coupled inductances 7 and 8. The secondary 8 of this transformer is connected to the grid 9 and the filament 10 of the tube 11. The plate 12 is connected through the primary 13 to the anode voltage supply line 14. The primary 13 and the secondary 15 form a second band amplifying transformer 13' forming the input circuit of the tube 16.

55 The out-put circuit of the tube 16 is coupled by means of the band amplifying transformer 17 to the detector tube 18 which may be provided with the grid leak 19 and the grid condenser 20. The out-put of the tube 18 includes an intermediate frequency resonant circuit frequently called a "filter circuit" consisting of a condenser 21 and the inductance 22. The inductance 22 forms a primary of the intermediate frequency transformer 23 having a secondary 24 included in 60 the grid circuit of the intermediate frequency amplifying tube 25. Two additional intermediate frequency transformers 26 and 28 may be provided with their respective tubes 27 and 29. The out-put of the tube 29 is coupled by intermediate frequency transformer 30 to the in-put circuit of the detector tube 31. This circuit consists of the secondary inductance 32, the grid leak 33 and the grid condenser 34.

65 70 75 80 85 Terminals 35 and 36 are provided so that the out-put of the detector 31 may be introduced into any suitable audio frequency amplifier (not shown).

The control station 40 may be provided 85 with power in any suitable manner for instance at its in-put with a cord and plug 41 for providing alternating current power to the primary 42 of the transformer 43, the amount of power being regulated by the rheostat 44 which serves as a gain control for the receiver. One secondary 45 of this transformer may have its terminations connected to the plates 46 and 47 of the full wave rectifier 48. The filament 49 of this rectifier may 90 be heated from the winding 50, and the filament 51 of the oscillator tube 52 may be heated from winding 50'.

95 100 The central point of the secondary 50 may be led through the smoothing inductance 54

and the feed back coil 55 to the anode 56 of the oscillator tube 52.

The filtering condensers 57 and 58 may be provided. The grid circuit of the oscillator 5 may consist of the inductance 59, the radiating loop 60 and the variable condenser 61. The grid return of the oscillator may be brought to the central point of resistance 62 which is also connected to a central tap of the winding 45.

10 The tubes 11 and 16 with their associated circuits form a band amplifier which will amplify with substantial uniformity over a desired band of frequencies, such as, the present broadcast band (550 to 1500 kilocycles). 15 A frequency such as, 50 kilocycles may be chosen as a resonant frequency of the filter transformer 23 and as the peak frequency of the following intermediate frequency amplifier system. The band amplifier is provided 20 to make up for the gain lost by not using a resonant in-put circuit.

In operation, the remote control station 40 is set in operation and the condenser 61 is 25 adjusted until the energy radiated from the loop 60 into the in-put of the receiver differs in frequency from the wave that it is desired to receive by the frequency chosen for the resonant frequency of the intermediate frequency amplifier system, thus producing a 30 beat frequency in the output of the tube 18 which is resonant to the intermediate frequency amplifier.

35 In a receiver such as just described the pick up system or antenna circuit 5, 7, 6 is more sensitive to the transmitted signal from the oscillation output 60 than the band amplifier coils which would normally be neutral with respect to external fields or otherwise effectively shielded.

40 The strength of the out-put of the receiver may be varied by varying the strength of the oscillations radiated from the loop 60 by various means such as the rheostat 44. The 45 loop 60 may preferably be in a horizontal plane, thus polarizing its radiation in a manner least liable to affect other neighboring receivers.

45 In Fig. 2 the band amplifier covering the desired receiving frequency band is indicated at 65, the first detector at 66, the intermediate frequency filter amplifier at 67, the second detector at 68, an audio frequency amplifier at 69 and an out-put conversion device such as a loud speaker at 70. 71 indicates an oscillating detector whose frequency may be adjusted or set by the manual control 72 at any desired value. In the in-put of this oscillating detector is connected the loop 73, and its 50 out-put is introduced along with the received signal into the in-put of the first detector 66.

55 Fig. 2a shows one method of connecting the component parts of the circuit of the oscillating detector 71.

60 65 The vacuum tube 71' has in its anode cir-

cuit the feed back inductance 78, which may be coupled to the coil 78' included in the grid circuit, the delivery coil 17', which may be coupled with the secondary of transformer 17 (Fig. 1) of the receiver proper ahead of the first detector 66 (Fig. 2), and the by-pass condenser 79. The usual direct current anode source is indicated by the letters + B and - B.

70 The grid circuit contains the grid leak "90", the grid condenser "91", to ensure the production of the necessary difference frequency, the feed-back coupling inductance 78', the condenser 72' and the pick-up device or loop 73.

75 The control box 74 or oscillator is constructed in any suitable manner and contains any suitable oscillator system and power source and is provided with the frequency adjustment 75 and amplitude adjustment 76. Its out-put circuit includes the loop 77. This 80 oscillator 74 and the frequency control circuit of the oscillating detector 71 may be preferably adjustable over a band of frequencies 85 considerably higher than those to be received.

90 For purposes of explanation, let it be assumed that the desired incoming wave has a frequency of 550 kilocycles and that the intermediate frequency filter amplifier 67 has a chosen frequency of 50 kilocycles. Let us also assume that the oscillating detector 71 95 has been adjusted to oscillate at a frequency of 5000 kilocycles. Then, if we adjust the control station 74 to emit a wave of a frequency of 5500 kilocycles, this wave will be 100 received and heterodyned by the oscillating detector 71 whose out-put will then have a frequency of 500 kilocycles. This is the correct frequency to heterodyne the incoming 550 kilocycles in the first detector 66 and will produce an output frequency of 50 kilocycles 105 which is correct for the intermediate frequency amplifier 67.

110 With this embodiment of my invention, several of these receivers, with their associated control stations, may be used in a single locality without interference between them, as by means of the adjustment 72 of the oscillating detector 71 any one of a number of bands may be chosen in which the control wave from the control box 74 may be confined, without overlapping other control bands.

115 The oscillator 74 and its responsive detector 71 may be designed for normal operation within any desired frequency limits or the oscillator 74 and the oscillating detector 71 may be provided with a multi-point switch (not shown) which may vary the inductance or the capacity of their respective oscillating circuits by several steps, such steps being 120 large enough so that the continuously variable control 75 of the oscillator will not permit of an overlap between the frequency bands represented by these steps. These steps may 125 be designated by letters or numerals, or in 130

any other suitable manner, so that if several of these receivers were installed close together, the control waves need never overlap. Interference between the controlling means of the various receivers will thus be avoided.

6 The out-put of the oscillating detector 71 may be introduced into the grid circuit of the first tube (not shown) of the band amplifier 65, thus greatly reducing the power required by the high frequency oscillator 74. The oscillator may then be of such low power as to preclude the possibility of interference with others.

Fig. 3 shows a method of applying my invention to ordinary tuned radio frequency 15 types of receivers. In this case a differential frequency converter unit 80 is provided which is inserted between the antenna system 81 and the input of a receiver 82. In case the input 20 of the receiver 82 includes a series condenser this condenser should be short circuited or a radio frequency choke placed across the input terminals to allow for the direct current anode flow. The remote control box oscillator 83 such as heretofore described and 25 shown in Fig. 1 is provided. The converter 80 as illustrated has a two-stage band amplifier and detector similar to that associated with tubes 11, 16 and 18 in Fig. 1.

30 In operation the tuning controls 84, 85 and 86 of the receiver 82 are adjusted until their associated circuits are resonant to the same frequency, which frequency may preferably be the lowest at which the receiver will operate. For purposes of explanation, let us assume that this frequency be 500 kilocycles and that the frequency band which it is desired to receive be from 1500 to 550 kilocycles. Then, if the oscillator 83 has a range of 35 2000 to 1050 kilocycles, 500 kilocycle beats can be produced at will in which case the radio frequency part of the receiver 82 will function as an intermediate frequency amplifier. The detector of this set 82 will now 40 function as a second detector for its audio frequency amplifier.

Owing to the fact that there is no resonant 45 selectivity at the incoming signal frequency and only the arithmetic selectivity remains, it may be found advisable to employ more than a single stage filter in the intermediate frequency circuits.

It is also advisable to choose such a resonant peak frequency for the intermediate 55 frequency filter amplifier that beats between any two transmitting stations will not be in resonance with this amplifier. For instance, with the present interval between broadcast stations of 10 kilocycles a frequency of 40 60 or 50 kilocycles can be produced by stations 3 or 4 intervals apart but if 45 or 55 kilocycles is chosen this will not occur. To ensure that no difficulties of this sort occur a several cell band-pass filter may be incorporated in the 65 filter amplifier which may have its cut-offs at

for example 51 and 59 kilocycles. To obtain best tone quality I prefer to adjust the portable oscillator 74 to a frequency which will place the carrier current in the band-pass filter close to one of its cut-offs or limits thus 70 allowing the full frequency range of the filter for one side band. By this method of tuning it is also possible to separate two stations which might differ in frequency equally but above and below the output frequency of the 75 oscillating detector if the intermediate carrier current frequency were midway between the limits of the band-pass filter employed.

I do not wish to limit myself to the detection methods, type of oscillating circuits, 80 number of stages, type of oscillator power supply or type of gain control except in so far as may be set forth in the appended claims and required by the prior art.

The particular combinations illustrated in 85 Figs. 1 and 3 are claimed specifically in my application #217,707, filed September 6, 1927.

I claim:

1. A remote controlled radio receiver, having a band pass amplifier, an oscillating detector connected with said amplifier and having a normally fixed frequency, said frequency being well outside of the response frequency of said band pass amplifier, pick-up 90 means connected with said oscillating detector, an independently portable oscillator having output means and of such variable frequency as will coat with said detector and pick-up means and produce beats with the 95 signals received through said band pass amplifier, a detector connected with the output of said amplifier, a filter-amplifier resonant to the output of said latter detector and another detector connected with the output of 100 said filter-amplifier, said portable oscillator having such characteristics with respect to the characteristics of the remainder of the apparatus that it will coat therewith within the range of an ordinary apartment. 105

2. A remote controlled radio receiver whose response frequency and response amplitude may be controlled from a distance having a band pass amplifier, an oscillating detector associated with said amplifier and having a normally fixed frequency, said frequency being well outside of the response frequency of said band pass amplifier, pick-up means associated with said oscillating detector, a separate oscillator of such variable 115 frequency as will produce beats within the frequency range of said band pass amplifier, output means associated with said separate oscillator, a detector associated with the output of said amplifier, a filter-amplifier resonant to the output of said latter detector and another detector associated with the output of 120 said filter-amplifier and an audio frequency amplifier associated with the output of said last mentioned detector, said separate oscil- 125

lator being movable with respect to the remainder of the apparatus and having radiating means coupled to its output means, adapted to co-act with said pick-up means within the area of an ordinary apartment, and means for varying the power of the output of the separate oscillator.

3. A remote controlled radio receiver comprising an input system including non-selective means for collecting and amplifying broadcast signals within a broadcast range of frequencies, separate, remote and portable means for producing control oscillations of various frequencies, means for varying the power of frequency of said control oscillations, means for selectively radiating control oscillations of a predetermined frequency, means connected with the input system for collecting the selected control oscillations to produce the desired intermediate frequency from the incoming signals, and means for reproducing the signals from said intermediate frequency.

4. In a radio receiver, a band amplifier having signal collecting means, a detector, oscillating and detecting means of normally fixed frequency higher than the frequency covered by said band amplifier and associated with said amplifier and having input means, a separately movable source of radiant oscillating energy having frequency control and power control and having means for transmitting to the said input means of said oscillating and detecting means and producing a lower frequency in the out-put of said oscillating and detecting means, means for combining said out-put frequency with incoming signal frequency so as to produce a still lower frequency, means for detecting said lower frequency, and audio frequency amplifier means associated therewith.

5. In a radio receiver, a band amplifier, a detector, oscillating and detecting means of normally fixed frequency higher than the frequency covered by said band amplifier associated with said amplifier and having pick-up means, an independently portable source of radiant oscillating energy having frequency control and power control and having means for transmitting to said oscillating and detecting means and coacting with said pick-up means to produce a lower frequency in the out-put of said oscillating and detecting means, means for combining said out-put frequency with incoming signal frequency so as to produce a still lower frequency and means for detecting said lower frequency.

6. A household receiving set comprising three units namely a receiving unit, a portable control unit and a reproducing unit, all adapted to be located in a single apartment, said control unit being entirely separate from the other units and adapted to be moved in the apartment from place to place with respect to the other units, said receiving unit in-

cluding a band amplifier having signal energy collecting means and adapted to receive and amplify all signals within a broad band of frequencies, said control unit including high frequency oscillation apparatus, power supply, amplitude control means and radiating means and said reproducing unit including means for amplification at a fixed super-audible frequency, detecting means and audio frequency sound converting means.

7. A radio receiving set adaptable for being controlled from a distance comprising local receiving apparatus and an unattached control oscillator having output means, said receiving apparatus consisting of an untuned radio frequency amplifier, a detector and a fixed local high frequency oscillator coupled with said amplifier and detector and having local pick-up means, an intermediate frequency band-pass filter amplifier, said local oscillator pick-up means being adapted for interacting with the output means of said unattached control oscillator to produce at said detector when receiving signals a resultant frequency equal numerically to a response frequency within the band of said intermediate frequency amplifier.

8. A radio receiver adaptable for being controlled by locally generated continuous waves, said receiver having a separately portable variable control oscillator with output means, an untuned radio frequency amplifier, a first detector associated with the out-put of said untuned amplifier, an intermediate frequency band-pass filter amplifier associated with the out-put of said first detector, a local oscillator of fixed frequency associated with said untuned amplifier and having separate pick-up means, a second detector connected to the out-put of said filter amplifier, means connected to said variable control oscillator to transmit continuous waves of variable frequency and intensity, said continuous waves being collected by said pick-up means and adapted to inter-act with said local oscillator and to produce in conjunction with the received signals a frequency in the out-put of the first detector equal numerically to a response frequency of the intermediate frequency filter amplifier and a second detector associated with the out-put of said filter amplifier, said second detector being adapted to produce audio frequency currents.

9. In a remote controlled radio receiver comprising, means for collecting signals of various frequencies within a predetermined band of frequencies, means for producing oscillations of fixed frequency outside said band, remote adjustable means for producing control oscillations of such frequency that when mixed with said fixed frequency oscillations a resultant frequency will be produced of a frequency differing from the frequency of the desired signal by a predetermined frequency, means for mixing the

fixed frequency oscillations with the control frequency oscillations to produce oscillations differing from the frequency of the desired signal by a definite final frequency, means for detecting the output of the collecting means and the output of the mixing means and producing oscillations of said final frequency, and means for amplifying and detecting said final frequency.

10. In a remote controlled radio receiver comprising, means for collecting and amplifying signals of various frequencies within a predetermined band of frequencies, means for producing oscillations of fixed frequency, remote adjustable means for producing control oscillations of such frequency that when mixed with said fixed frequency oscillations a resultant frequency will be produced of a frequency differing from the frequency of the desired signal by a predetermined frequency, means for mixing the fixed frequency oscillations with the control frequency oscillations to produce oscillations differing from the frequency of the desired signal by a definite final frequency, means for detecting the output of the collecting means and the output of the mixing means and producing oscillations of said final frequency and selective means for amplifying and detecting said final frequency and one of its side bands.

11. The method of selective radio reception controlled from a distance which comprises collecting all signals within a predetermined band of frequencies covering a plurality of signal channels, producing control oscillations at a distance having frequencies outside the said band of collected frequencies, mixing said control oscillations with oscillations of a fixed frequency different from the control oscillations by an amount other than the frequency of the desired signal, compounding the result of said mixture with the collected signals, detecting the results of said compounding and selecting an amplifying from the detected result a predetermined band of frequencies differing from all other received and produced frequencies.

12. The method of selective radio reception controlled from a distance which comprises collecting all signals within a predetermined band of frequencies covering a plurality of signal channels, amplifying and detecting said signals, producing high frequency oscillations of a controlled frequency, mixing said controlled frequency with a fixed frequency and producing a frequency having a predetermined difference from the frequency of the signal desired to be indicated, mixing the desired signal with said frequency having the predetermined difference and producing a frequency numerically equal to said difference and amplifying and redetecting the latter frequency.

13. The method of selective radio reception controlled from a distance which comprises collecting and amplifying all signals within a predetermined band of frequencies covering a plurality of signal channels, mixing the desired signal with a differing frequency so as to produce a lower frequency equal to the difference of said differing frequency from the frequency of the desired signal, producing said differing frequency by mixing a fixed frequency with a remotely generated adjustable frequency, and amplifying and detecting said lower frequency.
